BOWLING PIN WITH HOLLOW METAL CORE COMPRISING A PLURALITY OF SECTIONS

Alfred F. Bauer, Toledo, Ohio, assignor to National Lead Company, New York, N.Y., a corporation of New Jersey

Filed Feb. 26, 1963, Ser. No. 261,055
4 Claims. (Cl. 273—82)

This invention relates to a metal bowling pin and is particularly directed to a plastic covered, die cast pin having greatly improved balance, durability and ease of manufacture.

Bowling pins in the past have generally been made of wood and more particularly of hard maple. In recent years, the supply of the type of maple used for wooden bowling pins has diminished in this country, while the increase in popularity of the sport of bowling has produced a demand for greater and greater numbers of bowling pins. The typical wood bowling pins has several inherent disadvantages. One disadvantage is that the wooden bowling pin becomes marred and chipped after a relatively short time thus making it necessary that the pins be removed from service, turned down a lathe, and then refurbished by application of a new plastic outer layer. Another disadvantage is that the reduced neck section of a wooden bowling pin is very susceptible to failure by way of breakage.

Also, during the summer months, when the relative humidity is high the moisture in the air affects the bond between the wooden core and the plastic outer layer whereby they tend to become separated. During the subsequent winter months, or in periods of low relative humidity, the wood in the bowling pin shrinks up to five percent and the plastic outer layer has a tendency to become separated from the wooden core to such a degree that the pin must be taken out of service. When this happens the pins must be placed in a controlled humidity room for approximately 48 hours where swelling of the wood takes place and again provides proper contact between the plastic outer layer and the wooden core.

Since the rate of recovery is greater for plastic than it is for wood, upon impact between the wooden bowling pin and the bowling ball, the plastic "recovers" its original shape at a faster rate than the wooden core whereby there is an additional tendency of the plastic outer layer to separate from the wooden core.

One of the objections to prior art metal bowling pins was that some of them were constructed in two parts or halves and joined together with a longitudinal connection or seam. When impact occurred between the bowling ball and the pin, the bowling pin had a tendency to "split" along the longitudinal seam.

The metal portion of the pin has been formed by a sand casting process. When a sand casting process is used in producing a metal bowling pin core, the resultant metal core does not have desirable physical characteristics. Because of the inherent characteristic of the sand casting process, the wall thicknesses of the core cannot be controlled to close tolerances. The nonuniform wall thickness of the metal core produced by the sand casting process results in a bowling pin which is "unbalanced" and thereby unacceptable.

It is the primary object of the present invention to produce a metal die cast bowling pin, which is constructed to close tolerances thereby resulting in a balanced bowling pin.

Another object of the present invention is to provide a metal bowling pin of the same size, shape and weight distribution of a standard wooden bowling pin.

Still another object of the invention is to provide a

metal bowling pin which gives the same "sound" and "action" as does a standard wood bowling pin when struck by the bowling ball, or when the bowling pins fall upon the lanes or alleys.

5 A further object is to provide a bowling pin which can be kept in continual use throughout an entire bowling season.

Still another object of this invention is to provide a metal bowling pin which does not have a tendency to split or separate under the impact of a bowling ball.

10 Another object of this invention is to provide a metal bowling pin which has a "neck" section of greater strength and durability than a typical wood bowling pin.

Further objects of this invention will become apparent

15 from the following specification and drawings, in which:

FIG. 1 is a front elevation view showing a bowling pin embodying the invention;

FIG. 2 is a vertical cross-sectional view, taken along the line 2—2 of FIG. 1 and drawn on an enlarged scale, 20 wherein a portion of the "sound deadening" layer has been removed to show the use of reinforcing ribs. Several of the reinforcing ribs have been omitted in this figure for purposes of clarity;

FIG. 3 is a vertical cross-sectional assembly view of 25 another embodiment of the invention, in which only the three cast sections are shown;

FIG. 4 is a horizontal cross-sectional view, taken along the line 4—4 of FIG. 3 and drawn on an enlarged scale, 30 wherein an outer layer of plastic material and an inner layer of sound deadening material are shown; and

FIG. 5 is a horizontal cross-sectional view taken along the line 5—5 of FIG. 2, in which a portion of the inner sound deadening layer is shown.

Briefly, the present invention comprises a die cast metal 35 bowling pin which is to be used as a substitute for the presently used hard maple bowling pin. The metal bowling pin comprises a sectional hollow, die cast light metal (aluminum or magnesium alloy) core, said sections being joined together by a welding process, an adhesive bonding process, a pressure fit process, or by a combination of the preceding methods. A layer of sound deadening material is placed on the interior surface of the hollow metal core and a layer of a semi-flexible plastic material is formed over the outer surface of the metal core.

40 An embodiment of a metal bowling pin, according to the invention is generally indicated at 10. The metal bowling pin 10 comprises a hollow metal core 11 constructed of three hollow metal die cast sections namely: a lower "cup-like" section 12, an intermediate neck section 13, and cap section 14. The three sections of the 45 bowling pin, namely sections 12, 13 and 14, are joined together at joints 15 and 16 which are transverse to the longitudinal axis of the bowling pin. It should be noted that the lower transverse joint 16 is located at a point 50 above the point of impact P between a standard 16 pound bowling ball and the bowling pin 10 and the upper transverse joint 15 is located well above the point of impact. Because of the lack of a longitudinal joint and the positions of the transverse joints, at no time will a bowling 55 ball directly strike the bowling pin at a joint, therefore the tendency of the bowling pin to split apart at the joints is greatly reduced.

A plurality of integrally die cast and circumferentially spaced reinforcing ribs 17 are provided in one embodiment of the invention, on the interior surface of die cast sections 12 and 13. The reinforcing ribs 17 extend longitudinally on the interior surfaces of the bowling pin 10 and are formed so they extend beyond their respective castings 12 and 13 and engage frictionally with the body 60 of the adjacent casting. For example, a reinforcing rib 17a which is die cast integrally with lower cup-like section 12 extends past the lower transverse joint 16. The 65

exterior surface 18 of the reinforcing rib 17a has approximately the same shape as the surface 19 of the intermediate neck section 13 at the same horizontal plane. The reinforcing rib 17a is cast so that the upper portion which engages with intermediate neck section 13 has an exterior radius slightly greater than the interior radius of the intermediate neck section 13. Therefore when the castings 12 and 13 are joined together the upper portion of reinforcing rib 17a serves as a cantilever. The compression fit resulting from the difference in radii applies force along the surface of the cantilever which results in a counteracting moment which in turn applies force to the interior surface 19 of the die cast section 13.

These plurality of engaging ribs 17 reinforce the bowling pin 10 when it is struck by a bowling ball and also during the application of an outer layer of plastic material 25 as will become apparent hereinafter.

The three die cast metal sections 12, 13 and 14 are joined together preferably by the "Sciaky" welding method, which is a flash welding process in which the two sections to be joined are made electrodes. The Sciaky method is used because of its characteristic fast cycle of welding which confines the welding heat almost completely to the ends of the surfaces to be welded and thus prevents the body of the sections of the metal core 11 from overheating.

The intermediate neck section 13 and the cap section 14 can be joined together by other methods, for example, by the use of a resin-binding material such as an epoxy resin. Shoulders 20 are provided on the sections 12 and 13, and sections 13 and 14 respectively, to serve as guides to position the sections in a uniform manner, during the welding or bonding processes.

The production of the hollow metal core 11 by a die casting process results in a core which has extremely uniform wall thickness. For example, the wall thickness of the hollow metal core, in the instant invention, if measured in a plane perpendicular to the longitudinal axis of the bowling pin does not vary more than 0.0015 inch. It is very important in the metal bowling pin art that the wall thicknesses of the hollow metal cores be kept to extremely close tolerances so that the completed bowling pin is symmetrical and therefore "balanced." Such a balanced bowling pin cannot be produced, with any degree of consistency, by a sand casting process in which sand cores must be used.

FIG. 3 shows another embodiment of the invention which depicts another method of joining the individual sections 12, 13 and 14 together. In this method the die cast sections 12, 13 and 14 are cast with fingers 21 on the lower section 12 and fingers 22 on the intermediate section 13. The fingers 21 and 22 extend beyond their respective castings 12 and 13 and interengage with the body of the adjacent casting. This forms a very firm joint and when the two sections 12 and 13 are pressed together, the resiliency of the metal makes it virtually impossible to pull them apart. Intermediate neck section 13 and cap section 14 are joined in a similar manner.

After the assembly of die cast sections 12, 13 and 14, a rubber-like sound deadening material 23, such as a foaming polyurethane spray, is applied to the inner wall of each of the three sections 12, 13 and 14. The sound deadening material 23 is, for example, sprayed into the assembled die cast sections 12, 13 and 14, through an axial opening 24 which is formed in the bottom of lower cup-like section 12. This rubber-like sound deadening material 23 is provided on the interior surface of the hollow metal core 11 to reduce the resonance of the hollow metal core 11. After the sound deadening layer 23 is applied, the natural frequency of vibration of the pin is such that the sound of a standard hard maple bowling pin when it falls or is struck by a bowling ball is very closely reproduced.

After the three sections 12, 13 and 14 have been joined together by either the welding process, or the "press fit" 75

process, and after the sound deadening material 17 has been applied, an outer layer of plastic material 25 is applied to the assembled castings. Cap section 14 is provided with an axial opening 26 which engages with a centering pin located in the plastic coating mold (not shown). The outer layer of plastic material 25 is applied in the mold under pressure and the plurality of reinforcing ribs 17 prevent the hollow metal core 11 from deforming during this process. If reinforcing ribs are not used, the outer layer of plastic material 25 may be applied by low pressure molding process. After the outer plastic layer 25 is applied, a nylon insert 27 is adhesively or otherwise secured to the lower cup-like section 12. Insert 27 defines a shoulder 28 which guards the lower end 29 of the outer plastic layer 25 and serves to protect the lanes or alleys from excessive maring and is constructed in accordance with American Bowling Congress regulations.

The bowling pin 10 is constructed so that the weight of any segment of the bowling pin defined by two parallel planes which are perpendicular to the longitudinal axis of the bowling pin is the same as the weight of a similar segment of a hard maple bowling pin defined by the same planes.

The thickness of the outer plastic and the hollow metal core is determined by the relative density or specific gravity of the plastic used in the outer layer and the relative density or specific gravity of the metal used in the core with relation to the specific gravity of hard maple. Therefore, as previously discussed, a unit cross section of the embodiment of the present invention will weigh approximately the same as a unit cross section, taken at the same vertical position, of a hard maple bowling pin.

While the invention has been disclosed in conjunction with a specific form and disposition of the parts, it should be expressly understood that numerous modifications and changes may be made without departing from the spirit and scope of the appended claims.

What I claim is:

1. A bowling pin comprising a die cast hollow light metal core, said core comprising a plurality of die cast sections joined together in end-to-end relation, whereby the joints formed are transverse to the longitudinal axis of said bowling pin, at least one of said die cast sections having a plurality of integrally cast and circumferentially spaced reinforcing ribs extending longitudinally along its interior surface, said reinforcing ribs extending beyond one end of said die cast section and interengaging with the interior surface of the adjacent die cast section, a coating of sound deadening material on the inner surface of said metal core, a layer of a plastic material on the outer surface of said metal core, and a protective insert secured to the bottom of said bowling pin.

2. A bowling pin according to claim 1, wherein the wall thickness of said hollow metal core, if measured in a plane perpendicular to the longitudinal axis of said bowling pin, does not vary more than 0.0015 inch.

3. A bowling pin according to claim 1, in which said hollow metal core comprises three die cast sections joined together in end-to-end relation, whereby the upper and intermediate sections and the lower and intermediate sections are joined together at a point above the point of impact between a standard bowling ball and said bowling pin.

4. A bowling pin comprising a die cast hollow metal core, said hollow metal core comprising three die cast sections welded together in end-to-end relationship, whereby the joints formed are transverse to the longitudinal axis of said bowling pin and wherein the wall thickness of said hollow metal core, if measured in a plane perpendicular to the longitudinal axis of said bowling pin does not vary more than 0.0015 inch, at least one of said die cast sections having a plurality of integrally cast and circumferentially spaced reinforcing ribs extending longitudinally along its interior surface, said reinforcing ribs extending beyond one end of said die cast section and

inter-engaging with the interior surface of the adjacent die cast section, a coating of sound deadening material on the inner surface of said metal core, a layer of a plastic material on the outer surface of said metal core, and a protective insert secured to the bottom of said bowling pin.
